Primary Examiner — Vy N Koenig*Assistant Examiner* — Kimberly Barnes(74) Attorney, Agent, or Firm — Timothy T. Wang; Ni, Wang & Massand, PLLC(57) CLAIM

The ornamental design for a textile with pattern, as shown and described.

DESCRIPTION

The sole FIGURE is a plan view for a textile with pattern showing my new design.

The broken lines depict the boundary of the textile with pattern and forms no part of the claimed design.

1 Claim, 1 Drawing Sheet
